UNITED STATES PATENT OFFICE

2,567,046

TWO-COLOR WAND LIGHT ATTACHMENT
FOR FLASHLIGHTSGordon S. Anderson, Millbrook, N. Y., assignor to
Stewart R. Brown Mfg. Co., Inc., New York,
N. Y., a corporation of New York

Application June 9, 1950, Serial No. 167,145

7 Claims. (Cl. 177—329)

1

This invention relates to new and useful improvements in flashlights and has especial reference to attachment therefor to be used for signalling purposes.

An object of this invention is to provide a simple, compact, durable attachment which can be made effective by merely screwing or attaching it to the ordinary standard flashlight casing containing batteries to enable an elongate light-transmitting wand thereon to be used for effective signalling purposes especially in such locations as airfields.

A further object is to provide a device which is simple, mechanically compact, economical to manufacture, and capable of easy and quick assembly and disassembly for replacement and repair when necessary.

Further and more specific objects, features and advantages will more clearly appear from a consideration of the detailed specification herein-after set forth, especially when taken in connection with the accompanying drawings which illustrate a present preferred form which the invention may assume and which form part of the specification.

In brief and general terms, the invention is in the form of an attachment to be screwed or otherwise readily attached to the upper end of the flashlight casing of standard type and containing battery cells. The attachment is in the form of a metallic head having a flange to be screwed into engagement with the top of the casing and has a socket to receive a light-transmitting wand of material such as plastic disposed on the head in a direction in axial alignment with the longitudinal axis of the casing. The head has suitable bores to receive lamp bulbs and associated socket elements below the wand and adapted, when illuminated, to throw light of one or another color against the bottom of the wand so that the whole length of the wand is illuminated in this color to act as an effective signalling means. Suitable colored glass screens may be disposed over the lamp bulbs in their bores to transmit the desired color to the wand.

The head is also provided with a lateral opening into which is tightfitted a separate and self-contained switching unit which is electrically connected to enable the operator to use his thumb or finger to switch one or another of the lamps into circuit to give the proper color of light in the wand. The switch unit is integral and may be easily inserted and removed. The entire unit can be easily assembled and disassembled for replacement and repair. The head has a de-

2

pendent stem which contacts the center terminals of the upper battery cell. The end result of the invention is that the attachment is so self-contained with respect to the switch and bulb relations that all that is necessary to make it effective is to screw it on to the top of the ordinary casing to make all the connections automatically.

The present preferred form which this invention may assume is shown in the drawings, of which

Fig. 1 is a vertical longitudinal section taken on the line 1—1 of Fig. 2;

Fig. 2 is a similar view taken on the line 2—2 of Fig. 1;

Fig. 3 is a plan view of the device with the signalling wand element removed; and

Fig. 4 is a somewhat schematic view of the device with particular reference to the circuit connections involved.

Referring now merely to the specific preferred form of the invention which is shown in the drawings, it will be apparent that I have provided a simple, compact, durable, efficient device which can be readily screwed on to any standard flashlight casing to present an effective signalling device involving preferably a plastic wand extending from the top of the casing with cooperating switching means to permit light of different colors to be projected to be exhibited through said wand as a means for signalling which is especially useful in many instances such as in airports.

Essentially, the device which constitutes our inventive device is to be related to an ordinary standard flashlight casing 10 which may contain one or more battery cells 11 in the usual manner with the regular coil spring 12 at the bottom to make contact, and a metal strip 13 extending up inside the casing from the spring 12 to a point midway the casing where usually there is a button to be pressed to close the circuit. In this instance, the button had been eliminated and a stud 14 connected to the strip 13 extends through the casing and is fixedly connected to a metal strip 15 which extends up along the outside of the casing 10 and is bent over the top thereof as at 16. This strip 15 preferably lies in a groove formed in the side of the casing.

The attachment which constitutes the main feature of my invention is in the form of a light weight metal head 17, preferably of aluminum or similar light weight metal which is provided with a lower threaded flange 18 to be screwed on to the upper threaded end 19 of the casing. When

it is screwed on, it makes contact with the bend end 16 of strip 15 above mentioned on its upper face, the head 17 is provided with a socket 20 into which can be snugly inserted the signalling wand 21, and this may be held in place in any suitable manner in the socket by any suitable means such as a set screw 22. This wand is preferably of any suitable plastic material which is capable, when light is projected along its axis, of transmitting said light and becoming illuminated thereby along its entire length so as to become a very effective means for signalling, and because the area and length of wand thus illuminated is much more effective than if it were merely a light from a single bulb.

The head has a transverse wall 23 at the bottom of the socket in which the wand is disposed and dependent from this wall are a pair of bores 24 and 25 opening into the bottom of the socket below the lower face of the wand. At the top of these bores, which are shouldered, are disposed color discs 26 and 27 held in place by split rings 28 and 29. In the lower end of these bores are disposed metallic shells 30 and 31 which are snug-fitted therein. At their upper ends, these shells have therein threaded metallic sleeves 32 and 33 which form lamp sockets to receive the threaded lower ends of lamp bulbs 34 and 35 which may be screwed thereinto. At the bottom of these shells 30 and 31, which are bent inwardly as shown in 34', are disposed coil springs 36 and 37 on the top of which are disposed insulating plates 38 and 39 slidable within the shells to support contact members 40 and 41 respectively. These members project through the discs or plates 38 and 39 and contact the central terminal of the lamp bulbs, and at their lower ends are connected to circuit wires 42 and 43.

Thus far, it will be seen that the head supports the plastic signalling wand as well as the plurality of bulbs beneath the same which are related into the circuit and with suitable color discs to transmit light of one color or another against the bottom of the wand which will then become illuminated along its entire length in the respective color. Contact between the circuit and the bulbs is insured by the resilient pressure exerted on the insulating plates 38 and 39 to hold their supported contact in electrical association with the central terminal of the bulbs.

The head has a screw threaded stem 44 extending centrally down therefrom with a lower bore 45 in which is seated an insulating washer 46 which is so shaped as to line the bore and extend laterally across the bottom of the stem 44. A contact member 47 has an upwardly projecting stem 48 which projects upwardly into said washer. This contact member, or plate, 47 is adapted to rest as shown in the figures on top of the central contact 49 of the topmost adjacent battery cell. A suitable wire 50 is connected to this contact element 47.

The head is provided with a lateral opening 51 shown in Fig. 1 into which is snug-fitted a metallic switch casing 52. Within this switch casing is disposed an insulating block 53 supporting a shaft 54 to which a switch handle 55 is connected. At one end of the shaft 54 is mounted an oscillatable metallic switch arm 56. A spring 57 seated in the block 53 bears against the back of this arm to hold it in firm contact with a pair of circuit contacts 57 and 58 which are mounted in spaced position on an insulating plate 59 which closes the front of the switch box 52. This switch box is snug-fitted in the lateral opening 51 of

the head and is held in position by a set screw 59. It will thus be seen that the switch box is a separate unit which can be readily inserted into, and removed from, the head at will.

Referring to Fig. 4 which is a somewhat diagrammatic layout of the circuit connections, it will be seen that the base terminals of the bulbs are connected respectively to the contacts 57 and 58. The shells of the bulbs are connected by wires 60 and 61 to the metal body of the head itself. Of course it is understood that these wires 60 and 61 do not actually exist in the structure, but merely represent in the diagram the direct contact between the shells of the lamps and the metal casing of the head. The switch arm 56 is connected by wire 50 to the plate 47 as above described to make contact with the upper terminal of the topmost battery cell. From this, it will be perceived that the operator can grasp the device in his hand and readily manipulate the switch handle 55 to throw the contact to illuminate one or the other of the bulbs whereby the wand may be illuminated in different colors such as red and green. Of course the switch can be moved to the neutral position in which case neither bulb is in circuit. It is obvious that this device is a compact self-contained unit in the form of an attachment which, when it is assembled in the form shown, merely requires that it be screwed on to any standard flashlight casing in order to make automatic contact with the cells within the casing without any further connections or manipulations being made.

In a general consideration of the invention above described, it will be readily observed that the head 17 can be readily attached to the flashlight casing 10 by merely screwing the flange 18 on to the threaded upper end of the casing at which time the metal of the casing makes electrical contact with the strip 16 connected to the batteries in the casing.

The switch unit is assembled as a self-contained unit separate from the casing, and then is inserted in the lateral opening 51 and tightened in place after the necessary electrical wire connections are made. The dependent stem 44 automatically makes connection with the battery when the head is screwed into position. After this, the operator merely has to manipulate the switch handle 55 to throw the light from one or the other of the bulbs through the colored screens to have the proper color of light thrown against the lower end of the wand 21 so that it may along its entire length be illuminated to act as a very clear and effective signalling means. In airports or similar places this wand illumination is a positive, clear, and definite signal, is invaluable and has been proved in many practical every-day uses.

While the invention has been described in detail and shown with respect to the accompanying drawing, it is not to be limited to such details, since many changes and modifications may be made in the invention without departing from the spirit and scope thereof. Hence, it is desired to cover any and all forms and modifications of the invention which may come within the language and scope of any one or more of the appended claims.

I claim:

1. In a device of the class described, an attachment which includes a metallic head to be fastened to the end of a flashlight casing containing battery cells and having a socket therein disposed in line with the longitudinal axis of the

casing, and an elongate light transmitting wand disposed in said socket and projecting therefrom along said axis, said head having bores therein below the socket, and lamp bulbs supported in said bores, said head also having a dependent stem to contact a central terminal of an adjacent cell in the casing when the head is disposed on top of the casing.

2. A device according to claim 1 in which the head has a lateral opening with a self-contained removable switching unit disposed therein and connected in circuit with the bulbs, the casing and the cells.

3. A device of the class described which comprises a metallic head, a threaded flange thereon to adapt it to be screwed on to the top of a flash light casing containing batteries, said head having a socket in the top face thereof in line with the axis of the casing when applied, a light-transmitting elongate wand disposed in said socket, said head having bores extending downward therein from the bottom of the socket, and light bulb receiving assemblies disposed in said bores.

4. A device according to claim 3 in which the assemblies comprise a metal shell disposed in the bore, a bulb-receiving threaded sleeve within the shell, and spring-pressed contact means slidable within the shell below the sleeve to contact the

center terminal of a bulb inserted in the sleeve.

5. A device in accordance with claim 3 in which the head has a dependent stem to lie adjacent the upper battery cell in the casing and contact means insulatingly supported on the lower end of said stem and adapted to engage the center terminal of the cell.

10 6. A device in accordance with claim 3 in which the head has an opening to receive a removable self-contained switch unit which is connected to the batteries, the lamp bulbs and the head.

15 7. A device in accordance with claim 5 in which the head has an opening to receive a removable self-contained switch unit which is connected to the batteries, the lamp bulbs, and the head.
